ATTORNEY.

UNITED STATES PATENT OFFICE.

WILLIAM C. BRINTON, JR., OF KENNETT SQUARE, PENNSYLVANIA, ASSIGNOR TO
PHILIPS-BRINTON COMPANY, OF KENNETT SQUARE, PENNSYLVANIA, A COR-
PORATION OF PENNSYLVANIA.

SWITCH-BOX.

1,321,806.

Specification of Letters Patent.

Patented Nov. 18, 1919.

Application filed October 24, 1916. Serial No. 127,334.

To all whom it may concern:
Be it known that I, WILLIAM C. BRINTON, Jr., a citizen of the United States, residing at Kennett Square, county of Chester, and 5 State of Pennsylvania, have invented a new and useful Improvement in Switch-Boxes, of which the following is a full, clear, and exact description, reference being had to the accompanying drawings, which form a part 10 of this specification.

The object of my invention is to provide a closure for a switch and parts appurtenant thereto, as, for example, the controlling mechanism of an ignition system. More 15 specifically, the object of my invention is to provide a switch box that may be readily assembled and also readily disassembled to gain access to the contained mechanism. Preferred embodiments of my invention are 20 shown in the accompanying drawings, in which—

Figure 1 is a plan view of the switch box with cover plate partly broken away.

Fig. 2 is a vertical section through the 25 box shown in Fig. 1 with parts omitted.

Fig. 3 is a perspective view of the interior members of the box.

Fig. 4 is a view, similar to Fig. 2, of a modification.

50 The box comprises the following parts: The first part comprises a metal cylindrical casing *a* having at the top a flange *b* and at the bottom a flange *c*. Around the inside the casing is machined out for a short distance below the top, forming an annular shoulder *d*. The second part is a spider comprising a metal top *e* having (say) three downwardly projecting legs *f* at uniform distances apart. The third part is a disk 55 *g* of any suitable rigid non-shrinkable dielectric material provided with recesses *h* in its periphery corresponding to, and adapted to receive, the legs *f*. A fourth part is described hereinafter.

45 The top *e* is of a diameter corresponding substantially to the internal diameter of the casing *a* above the shoulder *d*. The legs *f* are not flush with the periphery of the top *e*, but are set within the same a distance 60 about equal to the width of the shoulder *d*. The thickness of the top *e* is equal to about the depth of the cut-out part above the shoulder *d*. The spider may, therefore, be inserted into the casing *a* from the top

until the top *e* contacts with the shoulder 55 *d*, and the legs *f* of the spider will have a free sliding fit against the inner wall of the casing. Before the spider is inserted in the casing, the disk *g* of non-conducting material is applied to the legs *f* by simply 60 sliding it on the legs edgewise until the under face of the disk is flush with the lower ends of the legs. The lower end of each leg is provided with a countersink alining with a screw threaded hole in the base of 65 the corresponding recess *h*, and the spider is attached to the disk by screws. The flange *e* conceals the lower ends of the legs *f* but otherwise performs no useful function, although this flange could be utilized 70 to support the disk if the supporting means at the top were omitted.

All the switch mechanism which is required to be insulated from the box or casing is mounted on the disk *g*, which forms 75 the bottom of the box. Thus, where the switch box is employed to contain the controlling mechanism of an ignition system, the bottom *g* carries the two binding posts *i*, the switch contacts *j*, the vibrator *k* and 80 the condenser *m*. The hole *o* in the top *e* is adapted to receive a turnable plug (not shown) carrying the member or members adapted to bridge the switch contacts.

Overlying and riveted to the top *e* of 85 the spider is a thin metal cover plate *p* which has a hole alining with the hole *o*. A bushing *p'* is fitted tightly in the two holes preserving their alinement. When the spider *e f* (carrying the plate *p*) and disk 90 *g* are inserted within the casing from the top, the plate *p* is screwed to the flange of the casing. This prevents the spider and disk from turning in the casing. Removing the screws permits the ready removal of the 95 spider, the disk *g* and the switch mechanism mounted on the latter.

In Fig. 4 the casing *a* is shown as provided with a bottom *r*, thus forming a cup for the reception of the spider and the disk of insulating material. The disk itself and its mode of attachment to the spider is the same as hereinbefore described except that it is provided with a knob *s* projecting downwardly from the disk through a hole 105 in the bottom *r*. The knob projects substantially below the lower face of the bottom *r* so that the metal binding post, the

threaded lower end *t* of which depends from the knob, cannot contact with the metal bottom of the box.

Having now fully described my invention, what I desire to claim and protect by Letters Patent is:

1. A switch box comprising a casing; a top plate and a bottom plate, the latter a non-conductor and fitting within the casing adjacent its lower edge; legs connecting the peripheral portion of the two plates and extending within the casing adjacent its inner circumferential wall, and switch mechanism mounted on the lower plate; the said plates and legs being removable from and insertible within the casing in the direction of the casing's axis; and means preventing the turning within the casing of the other elements specified.
2. A switch box comprising a casing; means applicable to and removable from the casing in the direction of the axis of the casing, said means comprising a top plate fitting within, and flush with, the top of the casing; legs depending from the plate and an insulating disk secured to the legs and adapted to the internal diameter of the casing; and a plate overlying and secured to said top plate and the upper face of the casing surrounding the spider: the top plate holding said legs and insulating disk in position within the casing.
3. A switch box comprising a casing; means applicable to and removable from

the casing in the direction of the axis of the casing, said means comprising a top plate, legs depending from the peripheral portion of the top plate and an insulating disk; both said legs and said disk adapted to the internal diameter of the casing and the disk being recessed in its periphery to receive the lower ends of the legs.

4. A switch box comprising a casing having an outturned flange at its top and cut away to form an internal annular shoulder; a spider composed of a top plate equal in depth to the depth of the cut-away part of the casing and resting upon said shoulder; legs depending from the top plate; and an insulating disk fitting within the casing and secured to said legs.

5. A switch box comprising a casing having an outturned flange at its top and cut away around its inner upper edge to form an internal annular shoulder; a spider composed of a top plate of a thickness equal to the depth of the cut-away part of the casing and resting upon said shoulder, and legs depending from the top plate; an insulating disk fitting within the lower end of the casing and having recesses in its periphery accommodating said legs; and a plate overlying and secured to the top plate and the flanged upper end of the casing.

In testimony of which invention, I have hereunto set my hand, at Philadelphia, Penna., on this 23rd day of October, 1916.

WILLIAM C. BRINTON, JR.
